UNITED STATES PATENT OFFICE.

HENRI LANGIAUX, OF PARIS, FRANCE, ASSIGNOR TO FRANCIS A. SHEA, OF BOSTON, MASSACHUSETTS.

SUPPORTING CASE FOR FLATIRONS.

Application filed September 7, 1928, Serial No. 304,556, and in France November 24, 1927.

The present invention relates to a supporting case for flat irons, and has for its object to provide a box or case which serves to contain the flat iron for transportation purposes, 5 and also as a support for the iron when the latter is in use. The said case is chiefly intended for flat irons of the electric type such as are in current use, and may be used to advantage by travelers, since the whole device 10 may be packed in a small space, in which the iron and its electric cord will be well protected.

The said case may consist of any suitable material, but is preferably made of metal. 15 It is open at the front end and is cut out at the top to form an open-ended slot adapted to receive the handle of the flat iron under certain conditions. Situated within the box or case is a reversible auxiliary support for the 20 main body of the iron, said support having a supporting face and also an open face. This auxiliary support is also reversible in position or invertible so that it may be used in either of two positions. When in one position it is 25 placed with the supporting face uppermost and in such position it forms a support for a flat iron which may be inserted into the box through the open end, said auxiliary support in such position supporting the flat iron 30 with its handle projecting through the slot in the upper face of the box or case. This is the relative position of the parts when the iron is being used and in such case when the iron is to be set down it is introduced into the 35 box or case and placed on the support, the handle of the iron entering the open slot and projecting above the box or case and thus being readily accessible.

If the auxiliary support is inverted so as 40 to place its open face uppermost then it forms a receptacle for the iron into which the latter may be placed when the iron is to be packed in the box for transportation purposes. When thus packed the entire iron is enclosed 45 in the box or case.

The box or case is of such a form that it 50 may support the iron in inverted position, that is, with the body of the iron resting on top of the box or case and the pressing surface of the iron uppermost, and with the handle depending through the slot in the top. When thus supported the iron can be used for steaming cloth or even for cooking purposes.

The auxiliary support is preferably provided 55 with a slot into which the handle of the iron

enters when the latter is in its inverted position thereby securely holding the iron in such position.

The invention further relates to certain accessory dispositions, which will be further 60 described.

In the appended drawings:

Fig. 1 is a perspective view of the outer case containing the flat iron.

Fig. 2 is a perspective view of the auxiliary 65 support of the iron.

Fig. 3 is a sectional view of the outer case and said support, the iron being in the operative position and resting upon said auxiliary support.

Fig. 4 shows the iron within the outer case and engaged in the auxiliary support so as to be easily transported.

Fig. 5 shows the iron in the inverted position, with its bottom part resting upon the 75 outer case and its handle engaged in the slot of the support.

Fig. 6 is a section on the line A—B of Fig. 3, with the flat iron removed.

The flat iron which is to be supported in 80 the box is indicated at 5 and is preferably of the electric type, it having the usual handle 6. The box or casing in which the iron is received is indicated generally at 1 and as shown in Fig. 1 it is open at the front end 2 85 and is provided on the upper face with a slot 4 which extends to the open end 2 of the box, said slot being widened at its open end as indicated at 3. The box is provided with up-standing projections 3'—3' on opposite sides 90 of the widened portion 3 for a purpose which will be presently described.

The box is shown as having a general trapezoidal shape, said box being narrower and shorter at the top than at the bottom, 95 the rear end 9 and the two opposite sides all inclining toward each other slightly from the bottom toward the top. The purpose of this construction is both to reduce the size of the case and to increase its stability.

Associated with the box 1 is an auxiliary support 7 adapted to be received within the case 1 and which is provided with a supporting face and an open face, thus being in the nature of a box itself into which the body of the iron may be placed through the open face. This auxiliary support 7 is invertible and is capable of being placed within the box 1 in either of the positions shown in Figs. 2 or 4. When in the position shown in Fig. 110

4 the open face of the auxiliary support is uppermost and said auxiliary support thus forms a receptacle for the iron 5 which is then enclosed entirely in the box 1, and this 5 is the position of the parts when the iron is packed for transportation. With the iron located in the auxiliary support as shown in Fig. 4 the handle 6 of the iron will be enclosed entirely within the box 1.

- 10 If the auxiliary support 7 is inverted into the position shown in Figs. 2 and 3 then the supporting face of said auxiliary support is uppermost and it forms a support or rest for the iron while being used. In this position 15 the handle 6 of the iron projects through the slot 4 and is accessible above the box 1. With the parts in the position shown in Fig. 3 the iron 5 can be easily introduced into the box and placed on the auxiliary support 7 20 or may be removed from the box because of the open-ended handle-receiving slot 4.

The box or case 1 is adapted to support the iron in the inverted position shown in Fig. 5 with the pressing face of the iron uppermost. 25 When in this position the body of the iron is resting on top of the box 1 and the handle 6 depends through the slot 4. The supporting face of the auxiliary support 7 is provided with a slot 10 in which the handle is received 30 when the iron is in its inverted position and said auxiliary support thus assists in holding the iron firmly in place. When in the inverted position the body of the iron lies in behind the projections 3'-3', the latter forming 35 stops to assist in holding the iron in place. The top slotted face of the box 1 is slightly inclined because the end face 9 is shorter than the front and hence when the iron is supported in inverted position as 40 shown in Fig. 5 the natural tendency of the iron is to retain its position. The upstanding projections 3' are curved slightly so as to offer no obstacle to the connection plug.

The auxiliary support 7 is formed with 45 the clamping plate 13 which is actuated by a screw 14 and which is adapted to engage the handle 6 and thereby assist in holding the iron firmly in the position shown in Fig. 5. It will be noted that when the auxiliary support 50 is in the position shown in Figs. 3 and 5 the upper face of said support inclines downwardly from the front to the rear. The advantage of this is that as the iron is inserted into the box or case as shown in Fig. 3 55 the natural tendency of the iron will be to move to the rear end of the box.

The box 1 is formed with a lower flange 12 at the bottom of the opening 2 which serves 60 as a stop to hold the auxiliary support in position. This support is shown as provided with a handle 8 by which it may be easily manipulated and removed from the box 1 and replaced therein in either of the positions shown in Figs. 3 and 4.

65 It will be noted that when the iron is com-

pletely enclosed in the box as shown in Fig. 4, the end 15 of the handle 6 is situated below the upper face of the box and beyond the slot 4 so that the whole combination of the iron, the auxiliary support and the box occupies 70 but a small space and the iron will be securely retained in the box for transportation purposes. When enclosed in the box as shown in Fig. 4 the iron can only be removed by first raising the auxiliary support 7 by means 75 of the handle 8 so as to release it from the flange 12 and then partially or entirely withdrawing said support from the box through the open end. When this is done the iron can be readily removed. 80

In certain cases, the handle 8 may be removed from the iron and may be stored in the said case.

Due to the fact that the iron may be inserted into the said case and may be suitably secured therein, the iron may be placed 85 in any position without any risk of its leaving the apparatus.

By reason of the auxiliary support 7, the hot iron may be insulated from the flat part 90 of the case and may be held in position by its upper inclined face, while facilitating the insertion of the iron into the said case.

When the iron is in the operative position, as shown in Figure 3, with the handle 6 95 alone extending from the outer case 1, it should be noted that any cloth articles which are adjacent the apparatus and which may be brought into contact therewith by accidental circumstances, will be protected 100 against all danger of burning, since they will be unable to enter into contact with the iron, whose heating surface is in fact situated in the interior of the said outer case.

By the use of suitable apertures 16 in the 105 sides of the auxiliary support 7, an air circulation can be set up between the lateral sides of the outer case and the sides of the support, in the space between these parts, This air circulation will prevent all overheating 110 in the interior of the case when the iron is in use.

When the apparatus is to be transported, the whole combination of the iron, the case and the auxiliary support will have a compact shape, and the electric wires may be placed in the upper part of the case, or may be wound around the handle of the iron. In the inoperative position of the iron, which remains stationary in the apparatus, the 115 parts are disposed as shown in Figure 4, and the electric wires are placed in the auxiliary support 7.

Claims:

1. A supporting case for flat irons comprising a box open at its front end and provided in its upper face with a slot extending rearwardly from the open end so as to permit of the insertion of the iron from front to rear, a removable auxiliary support within 120

5 said box, said support being provided with a supporting face and an open face, the main body of the iron when inserted in the box, resting on the supporting face with its handle protruding outside the box through the slot in the upper face of the box.

2. A supporting case for flat irons comprising a box open at its front end and provided in its upper face with a slot extending 10 rearwardly from the open end so as to permit of the insertion of the iron from front to rear, a support within said box, said support being provided with an upper, rearwardly and downwardly inclined iron sup- 15 porting face on which the pressing surface of the iron may rest, said inclined face having a slot to receive the handle of the iron inside the said support when the iron is placed in an inverted position in the said box 20 with its main body resting upon the upper face of said box.

3. A supporting case for flat irons comprising a box open at its front end and provided in its upper face with a slot extending 25 rearwardly from the open end so as to permit of the insertion of the iron from front to rear, an auxiliary support within said box, said support having an upper, rearwardly and downwardly inclined face providing a 30 rest for the iron in its normal position with its handle protruding outside said box and through the opening in the top, said inclined face of the support having a slot to receive the handle of the iron when the latter is sup- 35 ported in inverted position with its main body resting upon the upper face of the said box, and clamping means maintaining the iron in the last mentioned position.

4. A supporting case for flat irons comprising a box open at its front end and provided in its upper face with a slot extending rearwardly from the open end so as to permit of the insertion of the iron, a removable auxiliary support within the said box, said 45 support being provided with an upper rearwardly and downwardly inclined supporting face allowing of the storing of the iron in the box in its normal position with its handle protruding through the opening in 50 the top of the box, said inclined face having a central slot to receive the handle of the iron when the latter is supported in inverted position with its main body resting upon the upper face of said box, said support also having 55 an open face and being adapted to be placed in the box in an inverted position and in its inverted position forming a receptacle for the iron and supporting the latter entirely inside of the box with its handle abutting the 60 inner face of the top of the box.

5. A supporting case for flat irons, comprising a box having an open upper face to permit of the insertion of an iron in the box, a removable auxiliary support within said box, said support being provided with a sup-

porting face and an open face, the main body of the iron when inserted in the box resting on the supporting face with its handle protruding outside of the box through the opening in the upper face of the box. 70

6. A supporting case for flat irons comprising a box of a size to enclose the iron, said box being open at one end and having a handle receiving slot in its top which extends to the open end, and a support within the box having an upper face which inclines downwardly from the open end of the box toward the opposite end, said support being adapted to support the iron with the handle thereof projecting through the slot. 80

7. A supporting case for flat irons comprising a box of a size to enclose the iron, said box being open at one end and having a handle receiving slot in its top which extends to the open end, and an invertible hollow auxiliary support for the iron, located in said box and having an open face, said auxiliary support in one position constituting a receptacle for the iron and supporting it with the handle located within the box and in an inverted 90 position supporting the iron with the handle projecting through the slot, the supporting face of the auxiliary support when in the latter position inclining downwardly from the open end of the box toward the opposite end. 95

8. A supporting case for flat irons comprising a box of a size to enclose the iron, the said box being open at one end and having a handle receiving slot in its top which extends to the open end, a support within the 100 box for supporting the iron and with its handle projecting through the slot, said support also having a handle receiving slot to receive the handle of the iron when it is placed on the box in inverted position with the handle extending through the slot in the top of the box. 105

9. A supporting case for flat irons, comprising a box open at its front end and provided with an open upper face so as to permit of the insertion of the iron, a removable auxiliary support within said box, said support being provided with a supporting face and an open face, the main body of the iron when inserted in the box resting on the supporting face with its handle protruding outside the 110 box through the opening in the upper face of the box, said box being provided with an abutment on its base at the open front end, and adapted to prevent accidental displacement of said support. 115

10. A supporting case for flat irons, comprising a box open at its front end and provided in its upper face with a slot extending rearwardly from the open end so as to permit of the insertion of the iron, a removable auxiliary support within said box, said support being provided with a supporting face allowing of the storing of the iron in the box in its normal position with its handle protruding through the opening in the top of the box, 125 120 130

said face having a central slot to receive the handle of the iron when the latter is supported in inverted position with its main body resting upon the upper face of said box, said support also having an open face and being adapted to be placed in the box in an inverted position, and in its inverted position forming a receptacle for the iron and supporting the latter entirely inside of the box with its handle abutting the inner face of the top of the box.

11. A supporting case for flat irons, comprising a box trapezoidal in shape in vertical

cross section having an open upper face, to permit of the insertion of an iron in the box, ¹⁵ a removable auxiliary support within said box, said support being provided with a supporting face and an open face, the main body of the iron when inserted in the box resting on the supporting face with its handle protruding outside the box through the opening in the upper face of the box.

In testimony whereof I have signed this specification.

HENRI LANGIAUX.
